Primary Examiner — Ramzi Almatrahi*(74) Attorney, Agent, or Firm* — Young Basile Hanlon & MacFarlane, P.C.(57) **CLAIM**

The ornamental design for a camera lens attachment, as shown and described.

DESCRIPTION

FIG. 1 is a top, front and right side perspective view of a camera lens attachment of our new design;

FIG. 2 is a top, rear and left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines depict portions of the camera lens attachment that form no part of the claimed design.
